BOTTLE WASHING APPARATUS

Filed Feb. 6, 1928

UNITED STATES PATENT OFFICE

ALGOT ERICKSON, OF INDIANA HARBOR, INDIANA

BOTTLE-WASHING APPARATUS

Application filed February 6, 1938. Serial No. 252,229.

This invention relates to certain novel improvements in bottle washing apparatus and more particularly to a simple and efficient device which may be very economically manufactured.

The salient object of my invention is to provide a bottle washer which may be expeditiously associated with a suitable valve or faucet controlling the emission of steam or water.

Another object of the invention is to provide a bottle washer in which impingement members are provided which are adapted to be driven into the bottle by the fluid used to wash the same.

Another object of the invention ancillary to the foregoing is to arrange the device so that the impingement members may be repeatedly used.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is an elevational view depicting a preferred embodiment of my invention associated with a faucet of an approved design;

Fig. 2 is a sectional view taken substantially on the line 2—2 on Fig. 1;

Fig. 3 is a sectional detail view taken on the line 3—3 on Fig. 2; and

Fig. 4 is a perspective detail view of the inlet connection employed in my device.

In the drawings, wherein the preferred embodiment of my invention is illustrated, 10 indicates a faucet of approved design which in the present instance is adapted to control emission from a suitable water supply. It is to be understood however, that the device might be used in connection with a supply of steam or other suitable fluid. I provide a

connector 11 of any desired design which is adapted to be attached to the faucet 10 and a substantially U-shaped pipe 12 is directed to my improved bottle washer which is generally indicated at W in the drawings. In the present instance, I have illustrated a bottle

B of the restricted neck type but it is to be understood that my invention is not limited to such bottles and it is further to be understood that devices other than bottles may be washed in my device.

My improved bottle washer includes a cylindrical casing 13 into which a tapered cup 14 is adapted to be fitted. The bottom of the cup 14 and the sides thereof for a predetermined distance have a plurality of perforations 15 formed therein. The cup 14 is tapered so as to provide a space indicated by 16 in the drawings between the portion of the cup embodying the perforations and the interior of the outer casing 13. The bottom 17 of the cup at substantially the mid-point is formed to provide a downwardly extending neck 18. Adapted to have screw threaded connection with the interior of the neck 18 is a connector 19 which has a restricted opening 20 therein across which a pin 21 is adapted to extend for a purpose to be brought forth hereinafter. The interior of the connector 19 is adapted to be tapered as best illustrated in Fig. 2 and said connector is adapted to be 75 suitably connected to the pipe 12.

An upwardly extending conduit 22 is provided which is of a length sufficient to extend into the bottle B a distance substantially equal to that indicated in Fig. 1. Suitably secured to the conduit 22 adjacent the lower end thereof is a web member 23 having inverted truncated cone 24 therein, the base of which is adapted to bear against the interior of the cup 15 at substantially the point indicated in Fig. 2. The lower end of the conduit 22 extends through a funnel shaped member 25 which includes a neck portion 26 which is disposed around the conduit 22 and which extends therealong past the web member 23. 90 As is clearly illustrated in Fig. 2 the lower ends of the conduit 22 and the funnel 25 are held in spaced relation with respect to the bottom 17 of the cup 15. A plurality of impingement members indicated by 27 in the drawings are adapted to be introduced into the cup 15 and are disposed on the bottom 17 of said cup. These members 27 may be glass beads or shot or other analogous small particles.

In operation the faucet 10 is opened so as 100

to permit the fluid controlled thereby to flow through the pipe 12 into the connector 19. The connector 19 is adapted to have screw threaded connection with the neck 18 in order that said connector may be variably positioned in said neck so as to vary the siphon effect produced by the fluid emitted therefrom. The pin 21 in the opening 20 of the connector 19 prevents the members 27 passing into the pipe 12. By varying the position of the connector 19 and the neck 18 the force of the water emitted therefrom may be varied. The water emitted from the opening 20 picks up members 27 and carries them through the conduit 22, the funnel 25 preventing passage in any other direction. The full-line arrows on Fig. 2 indicate the path of the members 27 and the dotted-line arrows on this figure indicate the path of the water. Due to the force of the water by which the members 27 are emitted from the upper end of the conduit 22 the bottom of the bottle B will be struck with considerable force by these members and thus any sediment or other foreign matter collected thereon will be freed. The force with which this water and the impingement members is emitted will cause said members after striking the bottom of the bottle B to pass back along the sides thereof with a swirling motion and thus loosen any foreign matter on the sides of the bottle. The water and members 27 pass back down to the neck of the bottle B and thus back into the cup 15, it being apparent from Fig. 2 that the mouth of the bottle rests on the web member 23 when in operative position. The water passes out through the perforations 15 while the impingement members 27 are again entrapped in the bottom of the cup and again carried up to the conduit 22 by the fluid emitted from the opening 20. When the bottle B is cleaned the faucet 10 is closed and thus operation ceases. It is apparent from the foregoing that I have provided an efficient bottle washer which may be employed in a very simple manner and which is particularly adapted for household use. It is apparent that the device may be very inexpensively manufactured due to its simplicity of construction.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a bottle washing apparatus, a tubular housing, a cup-shaped member within said housing having the side wall portions

thereof tapered in a direction toward the bottom thereof whereby the lower portions of said wall portions are spaced from the interior walls of said housing, said cup-shaped member having perforations formed in said lower portions and the bottom thereof, a web member in said tubular housing disposed substantially midway between the top and bottom thereof having an inwardly directed funnel-shaped portion therein, a conduit extending axially of said cup-shaped member and having one end portion projecting above the upper end thereof, said conduit being secured in said web member, the lower end of said conduit being spaced from the bottom of said cup-shaped member, an outwardly flaring funnel member at the lower end of said conduit having the side thereof arranged in spaced relation to said cup-shaped member, means aligned with said conduit for directing a fluid through the bottom wall of said cup-shaped member, and impingement members normally disposed on the bottom of said cup-shaped member whereby fluid passing into said cup-shaped member toward said conduit will pick up and carry said impingement members through said conduit for discharge with said fluid from the upper end of said conduit.

2. In a bottle washing apparatus a tubular housing, a cup-shaped member within said housing having the side wall portions thereof tapered toward the bottom thereof whereby the lower portions of said side wall portions are in spaced relation to the cooperating inner wall portions of said housing, said lower portions and the bottom of said cup-shaped member having openings provided therein, a conduit extending axially of said cup-shaped member and having the lower end portion thereof arranged in spaced relation with the bottom of said cup-shaped member and having the opposite upper end portion thereof projecting beyond the end of said cup-shaped member, means for supporting said conduit in said cup-shaped member including a web member comprising radial fins, a funnel member including a stem portion extending around said conduit and including a head portion flaring outwardly therefrom at the lower end thereof, an inwardly directed truncated cone member disposed above said first named funnel member and carried by said web member and disposed to extend toward the head portion of said first named funnel member, means for connecting a supply conduit to the bottom of said cup-shaped member, the bottom of said cup-shaped member having a restricted opening therein in alignment with said supply conduit and said first named conduit, impingement members normally mounted on the bottom of said cup-shaped member whereby a fluid from said supply

conduit passing through said restricted opening will pick up and carry said impingement members through said first named conduit for discharge through the extended end thereof.

⁵ In testimony whereof I affix my signature.

ALGOT ERICKSON.
